UNITED STATES PATENT OFFICE.

PAUL R. WERNER, OF PHILADELPHIA, PENNSYLVANIA.

CURRENT-CONTROLLER FOR INDUCTION-COILS.

1,364,167.

Specification of Letters Patent.

Patented Jan. 4, 1921.

Application filed February 24, 1915. Serial No. 10,360.

To all whom it may concern:

Be it known that I, PAUL R. WERNER, a citizen of the United States, residing in the city and county of Philadelphia, State 5 of Pennsylvania, have invented new and useful Current-Controllers for Induction-Coils, of which the following is a specification.

It is the purpose of my present invention 10 to devise a contact making and breaking device that will control the electric current used in the primary winding of an induction coil for the purpose of producing sparks in a gap in the secondary winding.

15 It is particularly the purpose to devise a device that will produce either a single make of desired duration and a break, or a multiplicity of such makes and breaks at desired intervals to produce sparks of 20 a uniform character at very short intervals of time, as for instance to ignite the charges in an internal combustion engine.

It is a further purpose to devise an electrically operated current controlling mechanism 25 for induction coils that will cause a spark to be produced by said coil when the current is caused to flow through the mechanism and another spark to be produced when the current through said mechanism 30 is interrupted.

It is a further purpose to avoid the difficulties encountered in the operation of mechanically controlled devices, as heretofore employed, such difficulties arising principally through the effects of the inertia of 35 the various parts when operating at a relatively high speed.

My invention in its broad and generic scope consists of an induction coil spark-producer wherein a plurality of successive contacts of fixed duration are produced and controlled electrically instead of mechanically.

40 My invention further consists of a main circuit which, by means of a contact mechanism, will produce a current in a secondary circuit, such main circuit being controlled by a shunt circuit.

45 My invention further consists of means to utilize an electro-magnet in the shunt circuit to control the production of a spark in one of the circuits.

50 My invention further consists of a novel spark producer in which a single actuating member causes a contact to be made on both its advance and its return move-

ment, with a minimum consumption of electric current.

55 My invention further consists of a device of the character stated which eliminates the necessity of employing mechanical controlling means to open and close a circuit and one in which the contacts will be uniformly made, irrespective of the speed of the mechanism controlled.

65

My invention further consists of means for opening the shunt circuit if the contact parts stop on short circuit when the apparatus controlled by the spark is inactive.

70 My invention further consists of a spark producing system wherein the shunt circuit and the main circuit cannot be short-circuited.

75 Other objects and advantages of my invention will hereinafter more clearly appear in the detailed description.

For the purpose of illustrating my invention, I have shown in the accompanying drawings those forms thereof which are at present preferred by me, since the same 80 will give in practice satisfactory and reliable results, although it is to be understood that the various instrumentalities of which my invention consists can be variously arranged and organized and that my 85 invention is not limited to the precise arrangement of these instrumentalities as herein shown and described.

Figure 1 represents, diagrammatically, a 90 wiring diagram embodying my invention.

Fig. 2 represents a sectional elevation of a portion of Fig. 1.

Figs. 3 and 4 represent, diagrammatically, 95 wiring diagrams of other embodiments of my invention.

Similar numerals of reference indicate corresponding parts in the figures.

Referring to the drawings,

1 designates a source of electric supply such as for example a battery, which is electrically connected by the line 2 with a contact mechanism 3. The contact mechanism 3 comprises, in the present instance, a movable contact 4 carried by the free end of a spring arm 5 and the opposite end is 100 connected with a contact actuating member 6 which comprises a plate or bar having the reversely inclined faces 7. The member 6 has one end connected with binding post 8 and its opposite end 9 is outwardly 105 deflected to form a stop for the contact carrying member 5. 10 design-

- nates a stop to limit the movement of the member 6 in one direction. 11 designates the stationary contact, which is adjustably mounted and in communication with the line 5 12 leading to the primary coil 13, which is connected with the battery by means of the line 14, which, in the form illustrated, is connected with such battery by the ground. 15 designates a secondary coil and 16 designates a condenser which is shunted on the primary coil. The secondary coil is connected with the usual distributing means for the secondary circuit, which is well known in this art, and it has therefore been 10 deemed unnecessary to illustrate the same in detail. 17 designates a line communicating with the source of electric supply 1 and with an electro-magnet 18 which is in communication by means of lines 19 and 20 with a desired number of contacts 21, a four-contact arrangement being illustrated in the drawing, but it is of course to be understood that any desired number of contacts may be employed. 25 22 designates a contact arm which is in communication by means of a line 23 with the battery 1 and, for the purpose of illustration, this has been shown as through the ground. 30 Referring now to Fig. 2, 24 designates a rotatable shaft having a stop 25 with which normally contacts a weighted arm 26 which is pivotally carried, as at 27, by the shaft 24 or by an arm 22 secured to said shaft. 28 35 designates a contact which is freely movable in an aperture 29 of the contact arm 22, and the bottom of said movable contact 28 normally rests on the weighted arm 26. 30 designates the core of the electro-magnet 40 which coöperates with an armature 31 movably supported at 32 and provided with a spring 33 which normally maintains it against the stop 34, and a stop 35 is provided to limit the movement of said armature 31 in the opposite direction, and the position of such armature, when in contact with the stop 35, is indicated by dotted lines in Fig. 1. The operation of my induction coil spark producer will now be readily apparent to 50 those skilled in this art, and is as follows:— The type of contact mechanism illustrated in Fig. 2 and in Fig. 1 comprising the contacts 28 and 21, is shown for purposes of illustration only, and other forms can be substituted therefor, if desired, although the type illustrated is believed to be generally novel and is broadly claimed herein. Means are employed for controlling the shunt circuit, whereby the shunt circuit may 60 be automatically interrupted when the apparatus is inactive. When the shunt circuit is formed, the electro-magnet 18 is energized, thereby causing the armature 31 to move from its position seen in full lines to that seen in dotted lines against the tension of 65 the spring 33. During such movement, the end of the armature 31 which is preferably rounded or reversely inclined, coacts with the faces 7 of the contact mechanism 3, thereby causing the free end of the member 6 to move outwardly and permit the resilient arm 5 to move the movable contact 4 into and out of engagement with the stationary contact 11, and a contact of the requisite length is produced to produce a current in 70 the main circuit, which induces a current in the secondary circuit. The condenser 16 facilitates the production of the spark in the usual and well known manner. As soon as the current is broken in the shunt circuit, the 75 spring 33 causes the armature 31 to be returned to its normal position, at which time it is in contact with the stop 34, and during such movement, the contact mechanism 3 will be actuated in the manner hereinbefore 80 described and the current will be formed a second time in the main circuit to produce a second spark in the secondary circuit. The interval between the two successive sparks in the two successive contacts in the main 85 circuit will be controlled by the making and breaking of the shunt circuit. 90 The utility of this dual spark is that in case a pocket should be formed in the explosive charge and the first spark would fail 95 to ignite, the second spark will ignite the explosive charge. The contact mechanism 3, as will be apparent, is of such construction that it cannot stop on short-circuit and will make a contact of fixed duration, since when 100 the electro-magnet is energized, the armature cannot have anything but a full stroke, as is apparent. The contact mechanism for controlling the shunt circuit is illustrated as consisting of a 105 shaft 24 which is driven in any desired manner, whereby the contact carrying member 22 is caused to revolve. This causes the weighted arm 26 to fly outwardly and upwardly due to the centrifugal force, thereby 110 moving the movable contact 28 into position to contact with the stationary contact 21, and the making and breaking of the contact causes the energizing and deenergizing of the electro-magnet 18. This construction reduces 115 the consumption of current which would occur if the apparatus stopped on contact. The embodiment seen in Fig. 3 differs from that seen in Fig. 1 in that the contacts 120 in the controlling means are constructed to effect the opening and closing of the circuit in a shorter interval of time. Since the circuits are electrically the same as that in Fig. 1, similar parts have been given corresponding reference characters. The induction coil is illustrated as located in the main circuit anterior to the contact mechanism instead of posterior thereto as in Fig. 1. Instead of employing contacts as 21, I employ 125 130

- the contacts 36 which are of less operative length than the contacts 21, the result of which is that the shorter electrical contact caused by the engagement of parts 28 and 36 causes an earlier return of the armature 31. If desired part of the circuit may be returned through line 37 instead of 12 and 14.
- In the embodiment seen in Fig. 4 the wiring diagram is electrically the same and corresponding parts have therefore been given the same reference characters as in Figs. 1 and 2. The only difference is that the contacts 38 corresponding to contacts 21 in Fig. 1, or 36 in Fig. 3, are longer or of greater operative length and a lesser number are employed. The result of this is that the contact of 28 with 38 is of longer duration and the armature 31 is held in the position seen in dotted lines a longer interval of time.
- In the embodiment seen in Fig. 1, a single revolution of 22 will cause eight sparks to be produced. When 28 initially engages with a contact 21 the electromagnet is energized, thereby attracting the armature 31 to cause a contact to be made and broken at 4 and 11. The construction of the parts may be varied so that any desired length of contact will be made. When contact 28 disengages with the same contact 21, the electromagnet is deenergized and the means for returning the armature 31 illustrated as a spring 33 causes the return movement of the armature to its initial position and a second contact is made and broken at 4 and 11. The spring 33 is illustrative only and any other means may be employed to effect the return movement of the armature such as for example, a dashpot, magnet, or other mechanism.
- In Fig. 3 the operative length of contact formed by 28 and 36 is of shorter duration than that formed in Fig. 1 by 28 and 21, therefore the return of the armature 31 to initial position takes place sooner, the result of which is evident. If the dotted line 37 is used instead of lines 12 and 14, the current flow is interrupted when 28 is disengaged from a contact 36 so that no current at such time will flow through the main circuit so that on a single revolution of 22 the main circuit will be made and broken but four times instead of eight since four of the contacts made by the mechanism 3 will be ineffective.
- In Fig. 4 the operative length of contact between 28 and 38 is longer than the corresponding contact in Figs. 1 and 3, but two contacts 38 being employed. The engagement and disengagement of 28 with 36 causes the making and breaking of the circuit to occur at each quarter revolution of 22. This makes and breaks the main circuit four times in a single revolution of 22. By

varying the number and operative length of the contacts as 21, 36 or 38, the movement of 65 the armature 31 will be correspondingly varied.

In all the embodiments herein shown, electromagnetic means are used to make and break a contact of a given duration. 70

In ignition systems as heretofore constructed, a contact of fixed duration has been produced which was mechanically controlled by the engine, but in practice, contacts were often missed when the speed of 75 the engine increased beyond certain limits, at which time the lag of the moving part or parts was so great that the apparatus became inoperative.

In my present invention, the necessity of 80 mechanically controlling the making and breaking of the induction coil circuit is eliminated and the necessity of employing a multiplicity of moving parts which are mechanically operated is obviated. 85

The length of contact of the controlling means may also be varied by varying the dimension of the brush 28.

It will now be apparent that I have devised a novel and useful construction of a 90 current controller for induction coils, which embodies the features of advantage enumerated as desirable in the statement of the invention and the above description, and while I have, in the present instance, shown and described preferred embodiments thereof 95 which will be found in practice to give satisfactory and reliable results, it is to be understood that the same are susceptible of modification in various particulars without 100 departing from the spirit or scope of the invention or sacrificing any of its advantages.

Having thus described my invention what I claim as new and desire to secure by Letters Patent, is:— 105

1. A main circuit, a shunt circuit, an electromagnet in the shunt circuit, means controlled by the armature of the electromagnet when energized to make and break the 110 main circuit, and means to cause said armature to make and break the main circuit when the electromagnet is deenergized.

2. A circuit, a second circuit, an electromagnet in said second circuit, means controlled by the electro-magnet when energized to make and break the first circuit, and means to cause the armature of the electro-magnet to make and break the first circuit when said electro-magnet is deenergized. 115 120

PAUL R. WERNER.
